CN 303369774 * 9/2015

Primary Examiner — T Chase Nelson

Assistant Examiner — Kelly L Gross

(57)

CLAIM

The ornamental design for a blood analyzer as shown and described.

DESCRIPTION

1. Blood analyzer

1.1 : Perspective

1.2 : Front

1.3 : Back

1.4 : Left

1.5 : Right

1.6 : Top

1.7 : Bottom

1 Claim, 7 Drawing Sheets
